FOAMING COMPOSITIONS

Rupert C. Morris, Berkeley, and Webster M. Sawyer, Orinda, Calif., assignors to Shell Development Company, Emeryville, Calif., a corporation of Delaware

No Drawing. Application April 5, 1951,
Serial No. 219,504

14 Claims. (Cl. 252—117)

This invention relates to the improvement of the foaming properties of solutions of surface-active agents, including washing and cleaning agents and the like, and to new compositions having these improved properties.

While solutions of fatty acid soaps foam readily in soft water and give quite stable foams, there are many occasions on which it would be desirable to have more copious foam of greater stability. This is true, for example, in the preparation of fire-fighting foams and, indeed, in most uses of fatty acid soaps in hard water. The synthetic detergents which are resistant to hard water are generally deficient in foaming properties, particularly in respect to the quality and stability of their foam.

It has been proposed to overcome the deficiency of these surface-active agents by the addition of various compounds. Thus, albuminous materials derived from proteins, amine soaps of fatty acids and the like have been frequently suggested as desirable additives for fatty acid soaps in fire-fighting foam compositions, while higher alcohols, certain amides and fatty acid esters have been advanced as useful additives for synthetic detergents of certain types. An important object is to provide advantageous combinations of surface-active compounds with more desirable additives which impart superior foaming properties to the new compositions of the invention. A further object is the provision of detergent compositions of improved quality, and a special object is to provide washing and cleaning compositions based upon synthetic detergents which give a copious, long-lasting foam not obtainable with the detergent alone. Other objects and advantages of the invention will be apparent from the following description.

It has been found, in accordance with the present invention, that the foaming properties of surface-active agents in aqueous media can be materially improved by the addition of certain substituted sulfones. These sulfone compounds are those having in the molecule a hydrophobic chain containing about 8 to 18 carbon atoms and an imido carbonyl group

to which is attached, through not more than 4 intervening carbon atoms, a sulfone group directly linked to 2 carbon atoms. The R in the indicated imido carbonyl group may be a hydrogen atom or a hydrocarbon radical. The sulfone compound used may contain more than one imido, carbonyl and sulfone groups in the molecule but it is essential that at least one sulfone group of the type

be present in combination with an imido carbonyl group as above described in order to obtain the advantages of the invention.

The sulfone compounds which are essential components

2

of the new compositions may, for convenience of description, be divided into sub-groups in accordance with the form of attachment of the sulfone group to the imido carbonyl group in the molecule. Thus, one important sub-group of useful sulfone compounds is that in which the sulfone group is linked to the carbonyl carbon atom of the imido carbonyl group. An example of sulfone compounds of this type is the sulfone-substituted carboxylic acid amides which are represented by the general formula

wherein R and R³ represent hydrogen or a hydrocarbon radical, R¹ represents a hydrocarbon radical, R² represents a hydrocarbon radical linking the sulfone group —SO₂— to the carbonyl carbon atom by a chain of not more than 4 carbon atoms, and n is an integer which may be zero or one. At least one of the radicals R¹ and R³ is a hydrocarbon radical containing a chain of 8 to 18 carbon atoms, most preferably a straight or only slightly branched chain of 10 to 16 carbon atoms. Preferred compounds of this type are saturated amides of sulfone-substituted carboxylic acids.

One suitable method of preparing sulfone compounds of this type is by oxidation with nitric acid, for example, of the corresponding thioether-substituted carboxylic acids, which may be conveniently formed by addition of a mercaptan to an unsaturated carboxylic acid, and reaction of the sulfone-substituted carboxylic acid produced by the oxidation with a suitable amine. A typical synthesis of this type is the preparation of N-myristyl beta-(methyl sulfonyl) propionamide from acrylic acid, methyl mercaptan and lauryl amine in accordance with the following equations :

The first step in this synthesis, namely, adding a mercaptan to the starting olefinic compound, can be carried out in accordance with the methods of the following references to this type of reaction: Annual Reports of the Chemical Society (London), 1905, page 115; J. Am. Chem. Soc., vol. 60, pages 2452 and 2731 (1938), and vol. 61, page 70 (1939). The second step of oxidizing the sulfide to sulfone is a reaction described, for example, in J. Am. Chem. Soc., vol. 63, page 2941 (1941), vol. 68, page 973 (1946), vol. 70, page 3848 (1948), and vol. 72, pages 59 and 2858 (1950). The final step of producing the amide by reacting the carboxylic acid with an amine is a reaction described in J. Am. Chem. Soc., vol. 53, page 1879 (1931) and vol. 59, page 401 (1937), and in J. Org. Chem., vol. 8, page 473 (1943). Other sulfone-substituted carboxylic acid amides of this type which are effective foam-improving additives for detergents are:

N-lauryl alpha-(methyl sulfonyl) acetamide

3

alpha-(methylsulfonyl) acetic N-methyl palmitamide

N-methyl beta-(lauryl sulfonyl) propionamide

Cyclic as well as open chain sulfone-substituted amides of this type are effective additives in accordance with the invention. These cyclic sulfone compounds correspond to those of the foregoing general formula in which R¹ represents a divalent hydrocarbon radical directly connected to R² or those wherein R represents a divalent hydrocarbon radical linked directly to R¹ or directly to R². Representative effective compounds of this subgroup are, for instance:

3-decyl-5-sulfolanylcarboxamide

N-lauryl 2-sulfolanylcarboxamide

2-(1-methylhexadecyl)-5-keto-thiamorpholine-1-dioxide

beta-(lauryl sulfonyl) valerolactam

As previously pointed out, the sulfone-substituted compounds used to improve the foam properties of surface-active agents may contain a plurality of carbonyl and/or imido groups. Included among the useful amides of sulfone-substituted carboxylic acids of this type are, for example:

1-beta-methylsulfonylpropionyl)-3-octadecyl urea

1-(octadecylsulfonylacetyl)-3-methyl urea

3-tridecyl-4,6-diketo-m-thiazane-1-dioxide

1-(3-sulfolanylcarboxyl)-3-hexadecyl urea

The second important type of sulfone-substituted compounds which has been found to be especially effective in increasing the volume and stability of the foam of aqueous solutions of surface-active compounds is that comprising 5 the amides of sulfone-substituted amines which may be represented by the general formula:

10 wherein R¹ and R³ represent hydrocarbon radicals, at least one of which contains a chain of 8 to 18 carbon atoms, preferably a substantially straight chain of 10 to 16 carbon atoms, R represents hydrogen or a hydrocarbon radical, and R² represents a hydrocarbon radical linking the sulfone group to the nitrogen atom of the imido carbonyl group by a chain of not more than 4 carbon atoms. As is also the case with the amides of sulfone-substituted carboxylic acids previously described, the preferred sulfone-substituted compounds are saturated sulfone-substituted amides having a total of 11 to about 30 carbon atoms per molecule.

Sulfone-substituted amines which may be used as starting materials for the preparation of useful additives in accordance with the invention are readily produced, for 25 example, from olefinic amines by addition of a mercaptan and oxidation of the sulfide sulfur atoms of resulting product. These operations can be carried out as described in the journal articles previously referred to as showing how these reactions can be carried out. Reaction of 30 hydroxy sulfides such, for example, as 2-(methylmercapto)-ethanol with ammonia to replace the hydroxyl group by —NH₂ and conversion of the resulting amine to the corresponding amide of a suitable carboxylic acid, followed by oxidation with nitric acid or hydrogen peroxide, is another suitable method of synthesizing sulfone-substituted amides which are desirable additives. The 35 replacement of the hydroxyl group by —NH₂ is described, for example, in the text of Rodd "Chemistry of Carbon Compounds," volume IA, page 381, and the journal articles 40 there mentioned, for instance, V. Merz, Berichte, vol. 17, page 623 (1884), and Sabatier, Compt. rend., vol. 148, page 898 (1909). The succeeding steps of converting the amine to an amide and oxidation of the sulfide group to sulfone can be conducted as described in J. Org. Chem., vol. 8, page 473 (1943), or J. Am. Chem. Soc., vol. 59, 45 page 401 (1937), and J. Am. Chem. Soc., vol. 68, page 973 (1946) and vol. 70, page 3848 (1948), for instance. Typical amides of sulfone-substituted amines which are 50 advantageous in improving foaming properties in accordance with the invention are, for instance:

N-(2-methyl sulfonyl)-ethyl lauramide

N-(3-methyl sulfonyl)-propyl myristamide

N-(undecyl sulfonylmethyl) acetamide

2-(methyl sulfonyl) ethyl N-methyl capramide

Cyclic sulfone-substituted amides corresponding to the general formula

75

wherein R is a divalent hydrocarbon radical linking the nitrogen atom of the imido carbonyl group to R² or R³, or R¹ is a divalent hydrocarbon radical linking the carbonyl carbon atom of the imido carbonyl group directly to R² or R³, are also operative as additives for improving foam in accordance with the invention. Representative additives of this type are, for example:

Especially suitable are the amides of amino cyclic sulfones. These correspond to the above general formula when R³ is a divalent hydrocarbon radical linked directly to R². U. S. Patent 2,435,071 discloses and claims one type of sulfone compounds of this class which is eminently suitable provided a hydrocarbon radical, preferably an alkyl radical, of 8 to 18, most preferably 10 to 16, carbon atoms is present in the molecule.

and the like are typical of these preferred additives. However, other cyclic sulfone amides such as

etc. are also useful as additives for surface-active compounds.

While the use of individual sulfone-substituted amides has been emphasized in the foregoing, it will be under-

stood that mixtures of two or more such compounds are equally useful. Thus, a sulfone-substituted amine may be reacted with a mixture of suitable carboxylic acids, for instance, the mixed acids derived from animal or vegetable oils, fats or waxes, or a mixture of sulfone-substituted amines may be similarly reacted with one or more carboxylic acids to obtain a mixture of sulfone-substituted amides which are useful in the invention. Likewise a single amine or a mixture of such amines may be amidified with a plurality of sulfone-substituted carboxylic acids to obtain a mixture of sulfone-substituted amides which are effective foam-improving agents. Similarly, the amides of sulfone-substituted amines and sulfone-substituted carboxylic acids are useful additives for use in the invention. Suitable compounds of this type are, for instance:

30 It is also possible to use mixtures of preformed sulfone-substituted amides of the different types which have been described.

35 The amount of sulfone-substituted amide which it will be desirable to use in a given case will depend upon the particular sulfone-substituted amide or mixture of such amides which is chosen, the surface-active agent with which it is to be used and the intended use to which the mixture is to be applied. However, as a general rule, amounts between about 1% and 50% by weight of the surface-active agent present are suitable, and amounts between about 5% and about 30% are often most advantageous.

40 As previously indicated, the sulfone-substituted amides are effective in improving the foaming properties of a wide variety of surface-active salts of organic acids. The generally used surface-active organic acid salts are water-soluble salts of carboxylic, sulfonic, phosphoric and like acids and of sulfonic acid esters having a hydrocarbon chain of at least 8 carbon atoms in the molecule. Mixtures of two or more of these surface-active organic acid salts of the same or of different types may be used in the new compositions. Preferred organic acid salts are the alkali metal, e. g. sodium and potassium, or ammonium or amine, particularly the alkylolamine, salts.

45 Synthetic detergents are the especially preferred type of soap used in the new compositions because of the outstanding improvement obtained by the addition of the described sulfone-substituted amides to these compounds.

50 The sulfonates, i. e. the salts of organic acids having a $-\text{SO}_3\text{H}$ group which may be linked directly, or through an oxygen atom as in the sulfuric acid esters, to a hydrophilic group, are the preferred sub-group of synthetic detergents used in the invention. Among the salts of organic sulfonic acids which can be improved substantially in foaming properties are the salts of alkyl aryl sulfonic acids.

55 Examples of sulfonates of this type which have been successfully used are salts, particularly the alkali metal salts, of sulfonic acids such as are obtained by alkylating an aromatic hydrocarbon of the benzene series, particularly benzene or toluene, with an alkylating agent having preferably 8 to 16 carbon atoms per molecule such as an olefin, an olefin polymer or an alkyl halide, and converting the alkyl aromatic hydrocarbon thus formed into the corresponding monosulfonic acid which is then neutralized. U. S. Patents 2,467,130-32 and 2,477,383,

60 65 70 75

for example, describe alkyl aryl sulfonate salts which can be used, as can the keryl benzene, toluene, etc., sulfonates described in U. S. Patent 2,340,654, for instance. Instead of alkyl aryl sulfonate salts, alkyl sulfonic acid salts such as are obtainable by the methods of U. S. Patents 2,263,312 and 2,276,090, for example, are operative in the new compositions of the invention. Particularly desirable alkyl sulfonic acid salts are the 2-alkyl sodium sulfonates having a straight carbon chain of 10 to 18 carbon atoms.

As salts of sulfuric acid esters which are useful in the compositions, preference is had for those of 8 to 20 carbon atoms per molecule which may, for example, be produced by reacting an olefin or a mixture of olefins or one or more alcohols with sulfuric acid and neutralizing the sulfation product. Especially good results have been obtained with the alkali metal and ammonium salts, particularly the sodium salts of secondary alkyl sulfuric acid esters of 8 to 18 carbon atoms obtained from predominantly normal, terminally unsaturated mono-olefins such as can be obtained by cracking paraffin wax as described in U. S. Patent 2,152,297. The alkali metal salts of sulfuric acid esters of normal primary aliphatic alcohols such as may be obtained by hydrogenation of fatty oils such, for instance, as coconut, babassu, palm kernel, etc., oil or of sperm oil alcohols and the like, are other examples of detergents which are materially improved by the sulfone-substituted amides described.

While hydrocarbon sulfonate salts such as described above are a preferred type of synthetic detergent for use in the new compositions, improvement in foaming properties can also be obtained with substituted hydrocarbon sulfonate salts containing, for example, halogen, ether oxygen, carbonyl carboxyl, and like atoms or groups. Thus, water-soluble salts of sulfuric acid esters of hydroxy ethers of higher molecular alcohols such as the sodium sulfates of mono- or di-ethylene glycol mono-myristyl ether, or salts of carboxylic acid esters of hydroxy alkyl acid sulfates of which glycerine monolaurate monosodium sulfate and ethylene glycol monostearate monosodium sulfate are examples, are included among the sulfonate salt detergents which are benefited by the addition of a sulfone-substituted amide. This is also true of the water-soluble salts of sulfated carboxylic acid alkylolamides having detergent properties of which the coconut oil fatty acid ethanolamide sodium sulfates are representative. Corresponding detergents having a true sulfonic acid group in place of the sulfuric acid group of the foregoing compounds are likewise improved in foaming properties. These detergents include, for instance, the ethers of long chain alcohols with lower molecular hydroxy sulfonic acid salts such as the dodecyl ether of isethionic acid sodium salt, etc., the water-soluble salts of sulfonic acid-containing carboxylic acid esters, e. g., salts of sulfoacetic acid esters and alcohols of 8 to 20 carbon atoms and salts of higher fatty acids with hydroxy sulfonic acids such as isethionic acid, and salts of amides of amino sulfonic acids, such as N-methyl taurine, with higher fatty acids and the like. Instead of the foregoing sulfuric acid derivatives, the corresponding esters of phosphorus acids, particularly the phosphate and phosphite esters, may be used in the new compositions of the invention.

While the most pronounced improvement in foam properties have been obtained with the synthetic detergents which have been described, the sulfone-substituted amides are also useful additives for fatty acid soaps and the like, particularly where such soaps are used in hard water. Any of the water-soluble soaps from tallow, lard, fish oil, palm oil, corn oil, coconut oil, olive oil, and like fatty acids may be thus used.

In choosing the particular sulfone-substituted amide to be used in a given case, account should be taken of the chain length of the detergent with which it is to be employed, it being preferable to use sulfone-substituted amides having hydrophobic groups no longer than the hydrophobic group of the detergent involved. Most

preferably, amides having a hydrophobic chain of from about 4 carbon atoms less to about the same number of carbon atoms as the hydrophobic group of the detergent are used. Where mixtures of detergents and/or additives are being used, the average chain lengths should preferably have this relation to each other.

The chosen sulfone-substituted amide or mixture thereof may be incorporated in the detergent in a number of different ways. The detergent and additive may be mixed at the time of use or they may be premixed before use. It is often convenient to incorporate the additive during manufacture of the detergent. The sulfone-substituted amide may be mechanically mixed into the dry detergent or into a slurry thereof, or it may be added to an aqueous solution of the sulfonic acid or acid sulfate before the neutralization step in the process of producing detergents of these types.

The following examples illustrate some typical applications of the invention and show some of its advantages.

Foam tests were carried out with N-(3-sulfolanyl) lauramide as additive in a number of synthetic detergents of different types built with sodium tripolyphosphate and sodium sulfate so that the active detergent ingredient content was 18% by weight. The tests were made with 60 seconds' shaking in a mechanical shaking machine which insured reproducible results and in the presence of standard soil cloth. A 0.4% solution of detergent (total solids basis) in hard water (350 p. p. m. of calcium as calcium carbonate) at 55° C. was used.

Detergent	Amount of Sulfone-Substituted Amide Based on the Active Detergent Content	Foam Volume, ml.		
		Initial	After 10 Min.	After 20 Min.
Sodium dodecyl benzene sulfonate from propylene tetramer benzene	Percent None 5 11 16.5 22	79.8 81.5 82.0 86.0 87.0	38.7 56.0 63.0 70.0 70.7	18.4 29.5 30.0 41.5 48.3
Sodium secondary alkyl sulfates from cracked wax olefins of 10 to 18 carbon atoms sold under trademark "Teepol"	None 22	62.7 77.0	45.7 75.0	26.2 58.0
Sodium 2-normal tetradecane-sulfonate	None 22	72.8 79.5	39.1 76.5	16.3 56.5
Magnesium dodecyl benzene sulfonate, 32% active ingredient content (built with magnesium sulfate in place of sodium sulfate)	None 23	86.6 100.0	57.3 74.0	27.0 42.0

Similar good results are obtained when N-(3-sulfolanyl) myristamide, N-(2-methylsulfonyl ethyl) capramide, N-(2-dodecylsulfonyl ethyl) acetamide, beta-methylsulfonyl propionic lauramide, or other of the sulfone-substituted amides previously named are substituted for the N-(3-sulfolanyl) lauramide.

The effect of various amounts of sulfone-substituted amide additive on the foaming properties in soft and hard water of detergents was determined by tests carried out by a standardized hand-shaking procedure which gives reproducible results. When using a dodecyl benzene magnesium sulfonate derived from propylene tetramer benzene alkylate, built according to the following formula, as detergent

Percent by weight
Dodecyl benzene magnesium sulfonate
Na ₅ P ₃ O ₁₀
Na ₄ P ₂ O ₇
N-(3-sulfolanyl) lauramide
MgSO ₄ and Na ₂ SO ₄
Remainder

the following results are typical for detergent solutions

of 0.2% concentration at 55° C. in the presence of soil cloth:

Percent Sulfone-Substituted Lauramide additive	Soft Water (30 p. p. m. Ca)					Hard Water (325 p. p. m. Ca)					
	0	1	2	3	4	5	0	1	2	3	4
Foam Volume, ml.:											
Initial	66	70	75	73	70	75	70	75	75	75	90
Final (20 min.)	28	40	51	55	50	55	33	37	45	54	50

These results may be contrasted with those obtained when amides which do not contain a sulfonic group linked to the imido carbonyl group by a chain of not more than 4 carbon atoms are used. Examples of such amides are, for instance, caprylamide, dimethyl lauramide, lauramide, stearamide, lauryl lauramide, butyl capramide, dibutyl myristamide and N-lauroyl morpholine which, when added to the foregoing synthetic detergents under the same conditions, produce little or no improvement in the final foam volume or the foam stability. The results of representative machine shaking tests carried out as described above using propylene tetramer benzene sodium sulfonate as the detergent, and caprylamide and lauramide as examples of amide additives without the desired sulfone group, are as follows when 22% by weight of additive based on the active detergent content is employed:

Additive	Foam Volume, ml.		
	Initial	After 10 Min.	After 20 Min.
None	79.8	38.7	18.4
Lauramide	78.0	45.0	27.0
Caprylamide	75.0	38.0	15.0

The sulfone-substituted amide additives of the invention produce their remarkable improvement in foam properties without any undesirable effects upon the other advantageous properties of surface-active compounds. They produce a significant improvement in detergency, especially at low detergent concentrations, as can be seen from the following results of Launder-Ometer tests carried out with standard soil cloth in hard water using a propylene tetramer toluene sodium sulfonate detergent of 18% active ingredient content built with 45.5% of sodium tripolyphosphate, 30.5% sodium sulfate, 4% N-(3-sulfolanyl) lauramide and 1% carboxymethyl cellulose:

	Relative Detergency at a Detergent Concentration of—		
	0.1%	0.2%	0.4%
Without additive	18.5	52.5	57.5
With 4% of additive	31.5	55.0	60.0

It will thus be seen that the invention offers many advantages and is capable of wide application not only in respect to the detergents which can be employed and the sulfone-substituted amides which can be used therewith, but also in regard to the method of application of the new compositions. The new compositions are not only effective alone but can be used advantageously in combination with other materials. Any of the usual soap additives, including bleaching agents, perfumes, dyes, builders such as trisodium phosphate, tetrasodium pyrophosphate, sodium carbonate, sodium silicate, carboxymethyl cellulose, etc., may be included, as may any of the customary materials used in preparing emulsions and the like. It will therefore be understood that the invention is not restricted to the compositions given by way

of illustration nor by any theory proposed in explanation of the improved results which are obtained.

We claim as our invention:

1. A surface-active composition having improved foaming properties in aqueous solution which comprises anionic detergent of the group consisting of water-soluble fatty acid soap and water-soluble synthetic organic sulfonated and sulfated detergents, together with about 1% to about 50% by weight of the detergent of sulfone-substituted carboxylic acid amide having the sulfone group linked to the imido carbonyl group

15 wherein R is a member of the group consisting of the hydrogen atom and hydrocarbon radicals having not more than 18 carbon atoms) by a chain of not more than 4 carbon atoms and containing a saturated aliphatic hydrocarbon radical having 8 to 18 carbon atoms.

20 2. A surface-active composition in accordance with claim 1 wherein the sulfone-substituted amide is an amide of a sulfone-substituted saturated carboxylic acid.

25 3. A surface-active composition which comprises an anionic detergent of the group consisting of the water-soluble fatty acid soap and water-soluble synthetic organic sulfonated and sulfated detergents, together with about 1% to about 50% by weight of the detergent of N-(sulfolanyl) lauramide.

30 4. A detergent comprising an intimate mixture of at least one anionic water-soluble surface-active synthetic organic sulfonated salt detergent, together with 1% to 50% by weight of said surface-active salt detergent of saturated aliphatic carboxylic acid amide having a sulfone group linked to an imido carbonyl group

35 wherein R is a member of the group consisting of the hydrogen atom and hydrocarbon radicals having not more than 18 carbon atoms) by a hydrocarbon chain of not more than 4 carbon atoms and an aliphatic hydrocarbon radical of 8 to 18 carbon atoms which is not longer than the hydrophobic group of said synthetic organic sulfonated salt detergent.

40 45 5. A detergent comprising a mixture of at least one anionic water-soluble sulfonate salt detergent, together with about 5% to 30% by weight of said sulfonate salt detergent of a N-(sulfolanyl) amide of a saturated carboxylic acid having 10 to 16 carbon atoms per molecule.

50 55 6. A detergent comprising an intimate mixture of at least one anionic water-soluble alkyl aryl sulfonic salt detergent having an alkyl group of 10 to 16 carbon atoms, together with about 1% to about 50% by weight of said anionic water-soluble salt of a substituted sulfone having in the molecule a saturated aliphatic hydrocarbon chain containing 8 to 18 carbon atoms and an imido carbonyl group

60 65 70 wherein R represents a member of the group consisting of the hydrogen atom and hydrocarbon radicals having not more than 18 carbon atoms) to which is attached through not more than four intervening carbon atoms a sulfone group directly linked to two carbon atoms.

75 7. A detergent in accordance with claim 6 wherein the sulfone-substituted amide is an amide of a sulfone-substituted saturated carboxylic acid.

8. A detergent comprising an intimate mixture of at least one anionic water-soluble salt of an alkyl aryl sulfonic acid having an alkyl group of 10 to 16 carbon atoms, together with about 1% to about 50% by weight of said sulfonate of an amide of a higher fatty acid containing a hydrocarbon radical of 8 to 18 carbon atoms and an

amino cyclic sulfone, said amide having an imido carbonyl group

wherein R represents a member of the group consisting of the hydrogen atom and hydrocarbon radicals having not more than 18 carbon atoms) to which is attached through not more than four intervening carbon atoms a sulfone group directly linked to two carbon atoms.

9. A surface-active composition which comprises an anionic water-soluble, surface-active alkyl aryl sulfonate salt detergent, together with about 1% to about 50% by weight of the detergent of an N-(sulfolanyl) amide of a saturated carboxylic acid, which acid contains 10 to 16 carbon atoms per molecule.

10. A detergent in accordance with claim 4 wherein the surface-active organic acid salt detergent is alkyl sulfonate salt detergent and the sulfone group-containing amide is an amide of an amino cyclic sulfone.

11. A surface-active composition having improved foaming properties which comprises an anionic water-soluble synthetic organic sulfated detergent, together with about 1% to about 50% by weight of the detergent of an amide of a sulfone-substituted amine and a saturated aliphatic carboxylic acid, which acid contains a hydrophobic radical of 8 to 18 carbon atoms, the sulfone group being linked to the imido carbonyl group

wherein R represents a member of the group consisting of the hydrogen atom and hydrocarbon radicals having

not more than 18 carbon atoms) by a chain of not more than 4 carbon atoms.

5 12. A surface-active composition which comprises an anionic water-soluble, surface-active alkyl sulfate salt detergent, together with about 1% to about 50% by weight of the detergent of an N-(sulfolanyl) amide of a saturated carboxylic acid having an alkyl radical of 8 to 18 carbon atoms.

10 13. A surface-active composition having improved foaming properties in aqueous solution which comprises water-soluble fatty acid soap detergent, together with about 1% to about 50% by weight of the detergent of sulfone-substituted carboxylic acid amide having the sulfone group linked to the imido carbonyl group

wherein R is a member of the group consisting of the hydrogen atom and hydrocarbon radicals having not more than 18 carbon atoms) by a chain of not more than 4 carbon atoms and containing a saturated aliphatic hydrocarbon radical having 8 to 18 carbon atoms.

14. A surface-active composition in accordance with 25 claim 13 wherein the sulfone-substituted amide is N-(sulfolanyl) saturated fatty acid amide having 10 to 16 carbon atoms in the fatty acid radical.
